PARTITION SYSTEM

Louis R. Murdoch and Benjamin E. Cueny,
Grand Rapids, Mich.

Application April 26, 1951, Serial No. 223,016

2 Claims. (Cl. 20—1.11)

1

The present invention provides for partially isolating a particular area of floor space from surrounding sound or heat conditions. Table or desk space may be provided within this area, and the general purpose is to provide a place in which work can be done in some degree of comfort in a room in which conditions of radiant heat and ambient sound level are such as to cause difficulty of concentration. Partitions of a particular construction are provided with fittings permitting the units to be easily assembled in various patterns to isolate floor areas of corresponding patterns, and then disassembled whenever desired so they may be either moved or stored without the necessity of performing extensive labor in the process. The construction of these panels is preferably such as to provide insulation both against heat and against sound. While these partitions do not reach from floor to ceiling (and it is recognized that no absolute insulation against either heat or sound can be accomplished without such dimensions), it is nevertheless true that partitions constructed according to the present invention do serve to considerably lessen the amplitude of both the ambient noise level and the effect of radiant heat rays. It is preferable, of course, that such heat rays be not simply reflected from one place on the floor to another, but should be absorbed by one side of the panels. Suitable insulation prevents the heat from passing through the panels and substantially elevating the temperature of the opposite side where the isolated working area is located. If a simple reflecting surface were used, it would be necessary to give particular attention to the relative position on the floor of various partitioned areas so that one did not tend to reflect into another.

Table or desk units are preferably used in conjunction with the partitions discussed above, and these may be independently supported or secured directly to the partitions. At each point of juncture between partition panels, a corner post is provided; and this corner post may provide part of the support for the table or desk units as well. In order to permit light to enter the isolated floor area protected by the panels, while still retaining at least some of the panel characteristics over the full height of the structure, a section of preferably corrugated translucent material is positioned on top of the panels and in a generally vertical position. The corrugations and translucence of this material limit the passage of radiant energy through it, and to some degree interfere with the passage of sound waves from certain directions.

2

The construction of the panels themselves preferably involves a perforated material at the surface, and the perforations can be used as a means for supporting several types of attachments that are very useful in conjunction with the desk or table equipment. Bookcases, shelves, racks and similar items may be supported in a variety of positions simply by providing clips on the back of such units that may be inserted into the various perforations. The quantity of perforations makes it possible to position these items in almost any place that can be desired. The perforations—intended principally to deaden sound—serve double duty in this manner.

These features, and others related thereto, will be discussed in detail by an analysis of the particular embodiments illustrated in the accompanying drawings. In these drawings:

Figure 1 is a perspective view showing two partitions connected by a corner post, and showing an angular table unit and also a shelf unit in conjunction with the partitions.

Figure 2 is an end view of the panel assembly shown in Figure 1, with a portion of one of the panels broken away to show the internal construction.

Figure 3 illustrates the relationship of the panel and corner post attaching fittings.

Figure 4 shows a cross-section on the plane 4—4 of Figure 3, and illustrates the construction of the corner post.

Figure 5 is a perspective "exploded" view showing the relationship of the top of the panels, the corrugated translucent panel, and one of the supporting members for the corrugated panel.

Figure 6 is a section taken on the plane 6—6 of Figure 1 and showing the construction of a shelf unit and the method of securing it to the panel.

Referring to Figure 1, the panel units 10 and 11 are secured to a corner post 12, and form an angle of approximately 90°. Translucent panels 13 and 14 are positioned on top of the panels 10 and 11, respectively, and are held by the channel-shaped members 15, 16, 17, and 18. A shelf unit 19 is attached to the panel 11 in a manner to be discussed later, and a table unit 20 is shaped so as to conform to the angle between the panels 10 and 11. The table unit 20 is provided with the leg elements 21 and 22; and the central portion 23 of the table unit is supported at the corner post 12 by fittings which are not shown.

Referring to Figure 2, the panel units 10 and 11 are constructed as is indicated in the broken-away portion, and include the perforated inner

and outer panels 24 and 25, respectively, the space between these panels being filled preferably by insulating material 26. The panels 24 and 25 are preferably formed of a material having low heat and sound reflecting characteristics. A pressed fibrous material known generally as "Masonite" has proven to be satisfactory. Suitably spacer members such as is indicated at 27 are provided preferably at the top, middle, and bottom of the panel units, the perforated panels being secured in position by fastenings entering these members.

The attaching fittings which are used to secure the panels to the corner posts, and may be used to secure a series of panels together, are best illustrated in Figure 3. The corner post 12, being square in cross-section as is indicated in Figure 4, is provided on each of its four faces with female fittings as is indicated at 27. These fittings are formed as plates having a rectangular opening 28. The bottom of this opening forms a horizontal abutment against which the male fitting 29 engages. The fitting 29 is mounted upon the end 30 of the panel units. A suitable recess as is indicated at 31 is machined in the post 12 so as to fall opposite each of the apertures 28 in the plates 27. It is of course preferred that the plates themselves fit into recesses in the surface of the post 12 to present a continuous surface. It will be noted that the male fittings 29 have a downwardly-projecting extension 32 which is disposed to reach over and engage the lower extremity of the abutment provided by the lower end of the aperture 28. This arrangement of fittings makes possible the engagement and disengagement of the panels with the post by relative movement in the plane of the panels. Panels can be placed in position on the floor, and may be attached by slightly elevating them in an amount sufficient to permit the extension 32 to enter the aperture 28. The force of gravity will then maintain the panels in assembled position. Preferably, the inner edge 33 of the downwardly-extending projection 32 should be tapered in such a fashion that the engagement of the fittings forces the end 30 of the panel into close engagement with the post 12. The panels 10 and 11 may either receive their support from the engagement of the fittings outlined above, or may themselves rest with their weight supported by the floor area upon the footing members 34 or 35.

At the top of each of the panels 10 and 11, it is preferred that a groove as is indicated at 36 in Figure 5 be machined to provide added support to the bottom of the corrugated panels 13 and 14. The vertical channel-shaped supporting members 15, 16, 17, and 18 are preferably attached to the panels by means of dowel extensions 37 which fit into suitable bores 38 machined in the end pieces 39. The cut-away portion of the top of the channel-shaped member 18 shown in Figure 5 clearly indicates the groove 40 which forms the channel and which supports the corrugated panel 14.

Referring to Figure 6, a shelf unit 19 is shown

supported upon the inner corrugated panel of the insulating partition 11 by means of clips such as is indicated at 41. These clips are secured to the back of the shelf unit 19, and are adapted to enter one of the perforations 42 in the panels of which the partitions are formed. The shelf unit 19 is composed of the upper and lower members 43 and 44 and the central shelf 45. A sliding door 46 moves in a horizontal direction in grooves 47 and 48 in the upper and lower panels, respectively. The height of the door 46 is such that the upper edge may be inserted in the groove 47, and upward movement continued until the lower edge of the door 46 can be moved into the groove 48. The height of the door 46 and the depth of the grooves 47 and 48 are adjusted so that this manner of assembly is possible while still retaining the door 46 in position when supported on the bottom of the groove 48.

The particular embodiments which have been illustrated in the accompanying drawings and described herein are for illustrative purposes only, and are not to be considered as a limitation upon the scope of the appended claims. In these claims, it is our intent to claim the entire invention except as we are limited by the prior art.

We claim:

1. A partition system, comprising: a column; a plurality of insulating partition panels, said panels including a perforated surface member; shelf means; supporting means for said shelf means, said supporting means having a portion adapted to engage the perforations in said surface member; and attaching means disposed to unite said column and panels, said attaching means including inter-engaging members adapted to engage and disengage on relative movement substantially parallel to said column and panels, said column and panels having supporting surfaces in a common plane when said attaching means are engaged.

2. A partition system, comprising: a column; a plurality of insulating partition panels, said panels including a perforated surface member; shelf means; supporting means for said shelf means, said supporting means having a portion adapted to engage the perforations in said surface member; and attaching means disposed to unite said column and panels, said attaching means including inter-engaging members adapted to engage and disengage on relative movement substantially parallel to said column and panels.

LOUIS R. MURDOCH.
BENJAMIN E. CUENY.
